TEMPERATURE PROBE

Stephens N. Sato, San Diego, Calif., assignor to Ivac Corporation, San Diego, Calif., a corporation of California

Filed June 2, 1969, Ser. No. 17,477

Term of patent 14 years

Int. Cl. D10—09

U.S. Cl. D52—7

FIG. 1 is a perspective view of a temperature probe embodying my new design, showing the probe cover installed;

FIG. 2 is an elevational view along the length of the temperature probe shown in FIG. 1;

FIG. 3 is a right end elevational view of the probe shown in FIG. 1;

FIG. 4 is a left end elevational view of the probe shown in FIG. 1;

FIG. 5 is an elevational view along the length of the probe shown in FIG. 1 with the probe cover removed;

FIG. 6 is a right end elevational view of the probe shown in FIG. 5; and

FIG. 7 is a left end elevational view of the probe shown in FIG. 5.

I claim:

The ornamental design for a temperature probe, as shown.
